BUNDLING CRADLE

Chester A. Whissen, Lorain, Ohio, assignor to
 United States Steel Corporation, a corporation
 of New Jersey

Application June 3, 1952, Serial No. 291,428

7 Claims. (Cl. 214—10.5)

1

This invention relates to cradles for bundling elongated articles, such as pipes.

An object of the invention is to provide an improved bundling cradle which furnishes a rigid article receiving structure approaching circular outline for bundling articles introduced thereto and which automatically opens while a completed bundle is lifted therefrom.

A more specific object is to provide a bundling cradle which has a pair of pivotally mounted arms, each approaching semicircular profile, said arms being adapted to assume a rigid relation for receiving articles for bundling, and automatically opening while a completed bundle is lifted from the cradle.

In accomplishing these and other objects of the invention, I have provided improved details of structure, a single form of which is shown in the accompanying drawings, in which:

Figure 1 is a top plan view of a series of cradles constructed in accordance with the present invention;

Figure 2 is a side elevational view of one of the cradles shown in Figure 1;

Figure 3 is an end elevational view of the cradle;

Figure 4 is a sectional view taken on line IV—IV of Figure 3; and

Figure 5 is a fragmentary top plan view on a larger scale.

As shown in Figures 2 and 3, each cradle includes a rigid upright frame which is formed of a pair of spaced apart vertical side plates 10 and 12, a pair of end plates 13 and 14, and a top plate 15. The end and top plates preferably are welded to the side plates. The frame is fixed to a foundation as with angle irons 16 welded to the side plates and bolted to the foundation. The side plates are of approximately rectangular outline, but have relatively large U-shaped cutouts 17 which extend downwardly from their upper edges and have arcuate lower portions. The upper edges of the side plates opposite the top plate 15 slope downwardly toward these cutouts, as indicated at 18, to enable articles to roll therein gravitationally.

A pair of arms 19 and 20 are pivoted to the frame on pins 21, each of which extends between the side plates 10 and 12 and is located on a different side of the cutouts 17 (Figure 2). Arm 19

2

is formed of a pair of spaced apart side plates 22 and 23, the inner edges of which are of arcuate profile approaching a semicircle, cover plates 24 and 25 welded to these side plates, and a tubular bearing 26 also welded to the side plates and receiving one of the pins 21. Likewise arm 20 is formed of a pair of similarly shaped side plates 27 and 28, cover plates 29 and 30 and a tubular bearing 31 receiving the other pin 21. The semicircular profiles of arms 19 and 20 have substantially the same radius as the lower arcuate portion of the cutout 17.

The side plates 27 and 28 of arm 20 are spaced closer together than the side plates 22 and 23 of arm 19 and the lower portion of arm 20 can slide within that of arm 19 (Figures 4 and 5). The cover plate 25 of arm 19 terminates short of the lower extremity of the arm to permit such telescoping. Thus the lower portions of the arms can move past each other in parallel planes. The lower portions of the side plates 27 and 28 of arm 20 contain arcuate slots 32, while the lower portions of the side plates 22 and 23 of arm 19 carry a pin 33 which rides in said slots as the arms pivot about their pins 21. Thus the pin and slot act as stop means that limit pivotal movement of the arms. The lower portions of the arms carry counterweights 34 which tend to turn arm 19 clockwise and arm 20 counterclockwise to the closed position shown in solid lines in Figures 2 and 4. The outside upper portions of the side plates of the arms preferably have triangular extensions 35 which prevent articles from dropping between the outside of the arms and the frame.

In actual installations several cradles constructed as just described are situated in aligned relation as shown in Figure 1. Articles, such as pipes P, are placed on the sloping upper edge 18 of the frame and roll into the cutouts 17 and the space between the arms 19 and 20. These arms in conjunction with the frame form a substantially rigid article receiving structure approaching circular outline, but with an opening at the top, for bundling articles introduced thereto, since engagement of pin 33 with the lower end of slots 32 prevents further closing of the arms. After the cradles receive a sufficient number of articles to form a bundle of the desired size, the bundle is lifted therefrom by suitable handling.

equipment, not shown. As the bundle is lifted, it pushes against the undersides of the arms 19 and 20, which arms automatically pivot outwardly about their pivot pins 21, and thus open to the position shown in dot-dash lines in Figure 2. In this latter position they do not interfere with the removal of the bundle, but as soon as the bundle is clear, the counterweights 34 return them to closed position for receiving another load.

I have shown the cradle as equipped with means for preventing articles from dropping freely through too great a distance and thus incurring possible damage as they are introduced. This means includes a third side plate 36 in the frame spaced from the side plate 12 and of similar shape. Plate 36 is connected to plate 12 by end plates 37 welded to both side plates and by an extension of the top plate 15. A clevis 38 is connected between plates 12 and 36 at one side of cutouts 17 and a sprocket 39 at the other side. A chain 40 is connected to clevis 38, extends across the upper part of the cutouts 17, over sprocket 39 and into a hole 41 in the foundation. The lower end of the chain carries a weight 42. The articles drop on the chain 40, rather than directly into the cradle. The weight 42 is sufficient to support the articles partially, so that they are lowered gently into the cradle without damage.

While I have shown and described only a single embodiment of the invention, it is apparent that modifications may arise. Therefore, I do not wish to be limited to the disclosure set forth but only by the scope of the appended claims.

I claim:

1. A bundling cradle comprising a frame having a cutout extending downwardly from its upper edge, a pair of arms pivoted to said frame on opposite sides of said cutout, the opposed inner faces of said arms being of arcuate profile with each approaching a semicircle, said arms being relatively movable past each other in parallel planes at their lower end portions and having a closed position in which they form a rigid article receiving structure approaching circular outline with an opening at the top for bundling articles introduced thereto, and an open position in which they permit bundles to be lifted therefrom, and means normally returning said arms to their closed position.

2. A bundling cradle comprising a frame having a cutout extending downwardly from its upper edge, a pair of arms pivoted to said frame on opposite sides of said cutout, the opposed inner faces of said arms being of arcuate profile with each approaching a semicircle, the lower end portions of said arms being relatively movable past each other in parallel planes, stop means on the lower portions of said arms limiting their pivotal movement, said arms having a closed position in which they form a rigid article receiving structure approaching circular outline with an opening at the top for bundling articles introduced thereto and an open position in which they permit bundles to be lifted therefrom, and weighted means normally returning said arms to their closed position.

3. A bundling cradle comprising a rigid frame having a cutout extending downwardly from its upper edge, a pair of arms pivoted to said frame on opposite sides of said cutout, the opposed inner faces of said arms being of arcuate profile with each approaching a semicircle, the lower portions of said arms being relatively movable

past each other in parallel planes, a pin and slot connection at the lower portion of said arms limiting their pivotal movement, said arms having a closed position in which they form a rigid article receiving structure approaching circular outline with an opening at the top for bundling articles introduced thereto, and an open position in which they permit bundles to be lifted therefrom, and weighted means at the lower portions of said arms normally returning them to their closed position.

4. A bundling cradle comprising a rigid frame formed of spaced apart vertical side plates and connecting means, said side plates having U-shaped cutouts extending downwardly from their upper edges, a pair of arms pivoted to said side plates in the space therebetween on opposite sides of said cutouts, the opposed inner faces of said arms being of arcuate profile with each approaching a semicircle, the lower portions of said arms being relatively movable past each other in parallel planes, stop means on the lower portions of said arms limiting their pivotal movement, said arms having a closed position in which they form a rigid article receiving structure approaching circular outline with an opening at the top for bundling articles introduced thereto, and an open position in which they permit bundles to be lifted therefrom, and weighted means normally returning said arms to their closed position.

5. A bundling cradle comprising a rigid frame formed of spaced apart vertical side plates and connecting means, said side plates having U-shaped cutouts extending downwardly from their upper edges and having arcuate lower portions, a pair of arms pivoted to said side plates in the space therebetween on opposite sides of said cutouts, the opposed inner faces of said arms being of arcuate profile with each approaching a semicircle of substantially the same radius as the lower portions of said cutouts, the lower portions of said arms being relatively movable past each other in parallel planes, a pin and slot connection at the lower portion of said arms limiting their pivotal movement, said arms having a closed position in which they form a rigid article receiving structure approaching circular outline concentric with the lower portions of said cutouts, but having an opening at the top, for bundling articles introduced thereto, and an open position in which they permit bundles to be lifted therefrom, and weighted means normally returning said arms to their closed position.

6. A bundling cradle comprising a frame having a cutout extending downwardly from its upper edge, a pair of arms pivoted to said frame on opposite sides of said cutout, the opposed inner faces of said arms being of arcuate profile with each approaching a semicircle, said arms being relatively movable past each other in parallel planes at their lower portions, stop means on the lower portions of said arms limiting their pivotal movement, said arms having a closed position in which they form a rigid article receiving structure approaching circular outline with an opening at the top for bundling articles introduced thereto, and an open position in which they permit articles to be lifted therefrom, weighted means normally returning said arms to their closed position, the upper edge of said frame having a sloping portion allowing articles to roll into the space between said arms, and extensions on the outside edges of said arms preventing articles from entering the spaces between the

outsides of said arms and the inside of said cut-out.

7. A bundling cradle comprising a frame having a cutout extending downwardly from its upper edge, a pair of arms pivoted to said frame on opposite sides of said cutout, the opposed inner faces of said arms being of arcuate profile with each approaching a semicircle, the lower end portions of said arms being movable past each other in parallel planes, said arms having a closed position in which they form a rigid article receiving structure approaching circular outline with an opening at the top for bundling

articles introduced thereto and an open position in which they permit bundles to be lifted therefrom, stop means limiting pivotal movement of said arms toward their closed position, and means normally returning said arms to their closed position.

CHESTER A. WHISSEN.
